UNITED STATES PATENT OFFICE.

WILLIAM N. LEY, OF SPOKANE, WASHINGTON.

GAME APPARATUS.

1,146,306.

Specification of Letters Patent. Patented July 13, 1915.

Application filed April 25, 1914. Serial No. 834,502.

To all whom it may concern:

Be it known that I, WILLIAM N. LEY, a citizen of the United States, residing at Spokane, in the county of Spokane and State of Washington, have invented certain new and useful Improvements in Game Apparatus, of which the following is a specification.

This invention relates to games, the primary object of which is to provide a simple, yet scientific device which may be manufactured at a minimum cost.

Another object of the invention is to provide a game in which the ring-board or point bearing element is adjustable, thereby variating the science of the game at the option of the participants.

Still another object is to rotatably mount the alley or track of the game, thereby facilitating turning of the same from one of the participants to the other, since the game can be played by only one person at a time.

Other objects as well as the nature, characteristic features and scope of my invention will be more readily understood from the following description taken in connection with the accompanying drawings and pointed out in the claims forming a part of this specification.

Referring to the drawings: Figure 1 is a top plan view of a game constructed in accordance with my invention, Fig. 2 is a longitudinal sectional view showing to advantage the turning table upon which the alley is mounted, likewise, the supporting base, Fig. 3 is a transverse sectional view of the same taken on the line 3—3 of Fig. 2, and Fig. 4 is an elevational and sectional view, respectively, of one of the game pieces used in the present instance.

In the drawings wherein is illustrated the preferred embodiment of this invention, an alley or track A is provided comprising inclined side walls B, one end of each of which is in engagement with an end member C, said inclined side pieces B being provided with a pair of transversely extending slots D, which are adapted for sliding engagement with a ring-board or point bearing element E, the latter in the present instance comprising an ordinary plate or board, provided with a multiplicity of uniformly spaced-apart circular openings F, each of which is provided with a number thereover, the upper marginal edge of said board ex-

tending beyond the marginal edges of the inclined sides B.

A bottom G is mounted between the inclined sides B and extend to only approximately half-way the sides B, while a supplemental bottom or track proper H is provided, which in the present instance comprises a board, one end of which is engaged with the top of the bottom proper G, so as to dispose the supplemental bottom or track H at an inclination, the grade of which is consistent with the inclined sides B, said bottom H having a dead-line I extending transversely thereof, and being in connection with a semi-circular boundary line J, which is not to be encroached upon when actuating the game pieces K, each of which comprises a disk of wood, rubber or any other suitable material, provided with a central aperture, thereby facilitating the actuating of the game pieces by the operator.

A turn-table L is revolvably associated with the bottom G, permitting the entire alley to be rotated in the arc of a circle, so as to be placed directly in front of the person who is to play the game, especially adapting the same for use on a table or the like, where the participants of the game are seated about the table, thereby permitting the alley to be placed in front of any one of the players, after the other has finished. Elastic feet M are carried by the bottom G and H, thereby providing anchoring means for the alley when it is desired to actuate the members K thereon.

In playing the game, the game-pieces K are engaged with the supplemental bottom or track H within the semi-circular boundary line J, having the periphery thereof in engagement with the board or bottom H, the disk K being held between the thumb and third finger and the first finger placed behind the disk, so as to shoot or roll it over the track through the openings F in the ring-board E, the openings F having numbers thereover, so as to indicate the number of points secured by actuating the game-piece therethrough. Each of the participants in the game is given three game-pieces or disks K and if any two or three of the same are passed through the openings F in consecutive order, the numbers which represent the openings through which they pass will be added together and then multiplied by two or three, respectively. Of

course, if the game-pieces are rolled through the openings F, alternately, the numbers are only added together and not multiplied. If they after passing through the ring-board perchance return to the player on the track through the same openings through which it passed, or any of the other openings, the number of the openings through which it passed will be multiplied and then added and multiplied in the usual manner, as indicated above. Any predetermined number of points may be used, three-hundred usually being the game, when the ring-board is in the first groove, as indicated in Figs. 1 and 2 in the drawings, but when a more scientific game is desired, the ring-board E is removed from the first groove and placed in the second groove, thereby providing a gap between the terminal of the supplemental bottom H and the ring-board, causing more accurate judgment to be used, in order to actuate the game-pieces through the openings. The usual number of points for the lateral positioning of the ring-board E is seven-hundred points. Should the participant in the game slide his hand over the dead-line I, when actuating the game-pieces K, his roll will be considered void.

It will be understood that the above description and accompanying drawings comprehend only the general preferred embodiment of my invention and that various minor changes in details of construction, proportion and arrangement of parts, may be made within the scope of the appended claims and without sacrificing any of the advantages of my invention.

Having thus fully described my invention what I claim as new and desire to secure by Letters Patent is:

1. A game including a revolvably mounted alley, a ring-board adjustable longitudinally on said alley and game-pieces adapted to be moved on said alley and through openings in the ring-board for obtaining a predetermined score.
2. A game apparatus including an alley having a bottom terminating short of one

of the ends of the alley, an apertured ring-board mounted between the terminal of said bottom and the end of the alley and remote from both, and game pieces actuatable on the bottom of the alley and adapted to be passed through the apertures of the ring-board, for obtaining a predetermined score. 55

3. A game including an alley, a board provided with a plurality of openings, adjustable longitudinally in said alley whereby the science of the game may be variated, and game-pieces for actuation on the alley and through the openings of said board. 60

4. A game board including an alley, a ring-board adjustable longitudinally on said alley, and provided with a plurality of openings each of which bears a number, and game-pieces adapted to be rolled on said alley and through said openings for obtaining a predetermined score. 65

5. A game apparatus including an alley, a terminus of the bottom of said alley stopping short of one end of the alley, a ring-board, provided with numbered openings, adjustable longitudinally in the alley between said terminus and the end of the alley and remote from both at all times, 75 and game pieces actuatable on the alley and adapted to be passed through said numbered openings for obtaining a predetermined score.

6. A game including an alley, a ring-board longitudinally adjustable with respect to the alley and provided with a plurality of uniformly spaced-apart numbered openings, the bottom of said alley being inclined and having its highest point lying in close 85 proximity to said opening, and circular game-pieces adapted to be rolled on their peripheries on the inclined bottom and through said openings for obtaining a predetermined score. 90

In testimony whereof I affix my signature in presence of two witnesses.

WM. N. LEY.
